UNITED STATES PATENT OFFICE.

ALFRED N. GOLDSMITH, OF MOUNT VERNON, NEW YORK, ASSIGNOR TO RADIO CORPORATION OF AMERICA, A CORPORATION OF DELAWARE.

SOUND-REPRODUCING MACHINE.

Application filed September 9, 1922. Serial No. 587,067.

This invention relates to sound reproducing machines, and an object of the invention is to provide a machine which will be very convenient in operation and will be capable of affording a wider range of service than sound reproducing machines as formerly constructed.

To this end an important feature of the invention resides in the provision of a casing in which a horn is installed and a member mounted on the casing for movement relatively thereto and supporting a set of sound reproducing apparatus. The invention contemplates more particularly the provision of radio receiving apparatus connected to the horn of the machine and mounted in the cover, the cover being so mounted on the body portion of the machine casing and the radio receiving apparatus being so constructed and arranged that in the open position of the cover, the controlling elements of the radio receiving apparatus are disposed on the front face of the cover in convenient position for manipulation by the operator.

In accordance with another feature of the invention, a casing is provided comprising a plurality of portions connected together for relative movement, and sets of sound reproducing apparatus are mounted in respective portions of the casing. Preferably and in the illustrated embodiment of the invention, the sets of sound reproducing apparatus are provided with controlling elements, which in the normal positions of the portions of the casing are contained within the casing so as to be invisible, the controlling elements of the sound reproducing apparatus and the portions of the casing being, however, so constructed and arranged as to render the controlling elements visible upon relative movement of the portions of the casing. The controlling elements of one set of sound reproducing apparatus in the normal positions of the portions of the casing are located close to the controlling elements of the other set in order to conserve space within the casing, and the controlling elements of the respective sets are separated from each other upon relative movement of the portions of the casing, so as to render them readily accessible to the operator.

A further important feature of the invention resides in the provision in a casing comprising a main body portion and a cover portion of phonographic apparatus and radio

receiving apparatus mounted respectively in the body portion and the cover portion. The cover is preferably formed in two parts, one of which provides a top wall for the cover and the other of which is in the form of a member spaced from the top wall to provide a chamber between the wall and said member within which the radio receiving apparatus is mounted, and the controlling elements of the radio receiving apparatus are preferably extended through one of the parts of the cover for adjustment from outside of the chamber. In order to enable the exterior surface of the cover to present a smooth and unbroken appearance and to cause the controlling elements of the radio receiving apparatus to be disposed in a convenient position for actuation by the operator when the cover is opened, one of the parts of the cover is preferably formed as a panel supported within the other part, the radio receiving apparatus being mounted on the panel and comprising controlling elements extended through it for adjustment from the side of the panel which is exposed when the cover is opened, and the panel being perforated to receive the vacuum tubes of the radio receiving apparatus in order to enable the tubes also to be rendered accessible from the exposed side of the panel for inspection and replacement. The exposed side of the panel may be, and preferably is, also provided with means distinct from the controlling elements of the radio receiving apparatus for facilitating the adjustment of such elements.

In accordance with a still further feature of the invention, a two-branch horn is provided within the casing of the machine and two sets of sound reproducing apparatus are connected respectively to the branches of the horn. The machine also preferably comprises a device for controlling the operation of one of said sets of apparatus and means for automatically shutting off communication between the main body of the horn and one of its branches upon actuation of the device to cause communication of sound to the other branch. In another aspect, the invention contemplates the provision of a two-branch horn mounted in a casing and having phonographic apparatus connected with one of its branches and a telephone connected with its other branch, the telephone being in turn connected with radio receiving apparatus mounted in the cover portion of the casing.

The invention also aims to provide a radio receiver which may be employed as an attachment for phonographs, said attachment being constructed so as to enable it to be mounted in the casing of a phonograph without increasing the size of the casing or reducing the available size of any of its compartments.

Preferably and as shown, the attachment comprises a panel constructed to fit within the cover of a phonograph casing and radio receiving apparatus carried by the panel and connected to the horn of the phonograph.

Still other novel and useful features of the invention, including the provision of a door 15 removably mounted on one side of the phonograph casing to enable ready access to be obtained to the compartment which contains the horn and the parts associated therewith, will appear as the description proceeds and 20 will be pointed out in the appended claims.

In the drawings, in which like reference numerals designate like parts throughout the various views;

Fig. 1 is a front view of the upper part of 25 a machine embodying the invention with the cover of the machine in open position and with a portion of the machine casing broken away so as better to reveal the phonographic apparatus;

Fig. 2 is a view in perspective with the plate in the upper part of the casing removed so as to reveal the horn;

Fig. 3 is a perspective view of the panel supported in the cover and the radio receiving apparatus carried by it.

Fig. 4 is a perspective view taken from the rear of the machine and with the door on the rear side of the upper compartment of the casing in open position so as to reveal the horn 40 and the parts associated with it;

Fig. 5 is a view in sectional elevation from front to rear of the machine;

Fig. 6 is a plan view, partly broken away, of the construction at the juncture of the main 45 body of the horn and its branches;

Fig. 7, is a view of the machine in side elevation, partly broken away so as to show the radio receiving apparatus, the phonographic apparatus and the several compartments of 50 the casing;

Fig. 8 is a view showing the switch mechanism embodied in the radio receiving apparatus; and

Fig. 9 is a diagrammatic representation of 55 the circuit arrangement of the radio receiving apparatus.

The illustrated machine comprises a casing having a main body portion 2 and a cover portion 4 hingedly mounted at the top of the 60 body portion 2, as indicated at 6. The body portion 2 of the casing is of cabinet form and comprises compartments 8 for containing phonograph records, etc., and a compartment 10 in its end in which is located a horn 12.

65 The horn 12 flares outwardly from its rear

end to its forward end, designated by 14, where it is connected with a wooden tube 16 which constitutes an extension of the horn 12 and is flared in continuation of the sides of the horn 12.

70 Preferably and as shown, the horn 12 is formed at its rear end with two branches 18 and 20, the former extending upwardly and the latter extending first laterally and then forwardly within the compartment 10 of the 75 casing. The branch 18 of the horn is seated at its upper end in the top wall 22 of the body portion 2 of the casing and is connected above the wall 22 with a tubular arm 24 of known construction in sound reproducing apparatus 80 of the phonographic type. The arm 24 at its forward end carries a sound box 26 which may also be of known construction and arrangement. The phonographic apparatus of the machine further includes a plate 28 mounted in an opening 30 in the wall 22 and a turn-table 32 journaled on the plate 28 and arranged to be rotated by a spring motor 34 supported on the under side of the plate. The turn-table 32, is adapted to have a phonographic record placed thereon, and in the operation of the phonographic apparatus the sound box 26, on the arm 24, is thrown forwardly from the position shown in Figs. 2, 5 and 7 in a known manner to cause a needle 35 95 on the sound box to engage with and ride upon the record.

90 The sound box 26 constitutes an element by means of which the operation of the phonographic apparatus may be controlled, and the phonographic apparatus also preferably comprises other controlling elements (not shown) of the kind usually provided for governing the rotation of the table 32.

100 The lateral branch 20 of the horn 12 is connected to a second sound reproducing apparatus which is of the radio receiving type. As shown, the branch 20 is gradually tapered inwardly to its forward end where it is provided with a telephone 36 connected with the radio receiving apparatus. The cover portion 4 of the casing of the machine is preferably constructed in two parts, one of such parts being in the form of a panel 40 supported within the other part and spaced from the top wall 42 of the other part to provide a chamber 44 between the parts. The chamber 44 of the two-part cover is adapted to contain radio receiving apparatus, and in order to enable the chamber to be made of sufficient size to contain the radio receiving apparatus and yet avoid mechanical interference with the phonographic sound box 26, even though the space within the cover is small, the panel 40 may be inclined downwardly from the rear end to the forward end of the cover, with relation to its top wall 42, as clearly shown in Figs. 5 and 7.

110 In the illustrated construction, the radio receiving apparatus comprises a primary in-

ductance coil 46 mounted on the panel 40, Fig. 3, in coupled relation with a smaller coil 48, which is interposed in the circuit of a secondary inductance coil 50. The primary and 5 secondary circuits of the radio receiving apparatus include condensers 52 and 54 respectively. As shown the condensers are of the type comprising semi-circular plates which are alternately fixed and movable. The movable 10 plates of the condenser 52 in the primary circuit are mounted on an arbor 56 which extends through the panel 40 of the cover and is provided on the exposed side of the panel outside of the chamber 44 with a disc 58 co- 15 acting with a pointer 60 carried by the panel. Fast on the end of the arbor 56 within the chamber 44 of the cover is a relatively large spur gear 62 meshing with a small pinion 64 fixed to the end of a stud shaft 66. The shaft 20 66 is also extended through the panel 40 and is provided on the exposed side of the panel with a knob 68 which may be turned to adjust the condenser.

The condenser 54 in the secondary circuit 25 of the radio receiving apparatus is similar in general construction to the condenser 52 in the primary circuit and includes an arbor 70 extended through the panel 40 and provided on the exposed side of the panel outside of the 30 chamber 44 with a disc 72. In order to guide the user of the machine in adjusting or tuning the radio receiving apparatus, the disc 72 is preferably graduated or indexed with its front face, as clearly appears from Fig. 1, 35 and has associated with it a pointer 74 carried by the panel 40. Mounted on the end of the arbor 70 within the chamber 44 is a spur gear 76 which meshes with a small pinion 78 on a stud shaft 80, also extended through the panel 40 of the cover and provided on the exposed side of the panel with a knob 82 by which the condenser 54 may be readily adjusted.

The radio receiving apparatus comprises 45 vacuum tubes of the three electrode type, and the panel 40 of the cover 4 of the casing is perforated so as to enable the vacuum tubes to be rendered readily accessible for inspection or replacement from outside of the chamber 44, or in other words, from the side of the 50 panel 40 which is exposed when the cover 4 is in open position. In the illustrated embodiment of the invention, five vacuum tubes designated 84, 86, 88, 90 and 92 are employed, and the panel 40 is formed with a single rectangular opening 94, extending substantially from side to side of the cover 4 and containing a similarly shaped plate 96 spaced at its edges from the edges of the opening 94 so as to be freely movable relatively to the panel 40. 55 The plate 96 is provided on its exposed face with supports 98, Figs. 5 and 7, upon which the vacuum tubes are mounted in substantial parallelism with the plate 96. An apertured plate 99 is mounted on the panel 40 within the 60 chamber 44 in such a position as to prevent

access to the parts within the chamber 44 from being obtained by pushing back the plate 96 in the opening 94 of the panel. In order to prevent shocks to which the cover 4 of the casing may be subjected from being 70 transmitted to the vacuum tubes 84-92, the plate 96 is yieldably supported on the panel 40. As shown, the supporting means comprises posts 98 located adjacent to the corners of the plate 96 and connected by relatively 75 stiff coiled springs 100 with posts or screws 102 mounted on the panel. The springs 100 may be filled with absorbent cotton or other suitable material for damping any vibrations of the plate 96, caused by movement of 80 the cover. It is recognized that the arrangement of the vacuum tubes with relation to the panel 40 may be widely varied; for example, the tubes may be located in separate openings in the panel and may be disposed at right 85 angles to it.

The circuit of the secondary inductance coil 50 and condenser 54 is connected to the grid of one of the vacuum tubes, for example, the tube 84, the plate circuit of the tube 84 90 including a switch 104 at the left hand end of a switch block 106, Fig. 3, mounted on the panel 40. As shown, the switch 104 includes a segment 108 composed of brass or other suitable metal, four contact studs 110, and a contact member 112 carried by a member 114 pivoted centrally on the switch block 106 and composed of insulating material. The contact member 112 comprises parts arranged for engagement with the segment 108 95 and one of the four contact studs 110 depending upon the position of the member 114 on the switch block 106.

Each of the four contact studs is connected with the primary coil of one of four radio 105 frequency transformers 116, supported on the panel 40 within the chamber 44 of the cover 4, the secondary coils of the transformers 116 being connected to each of four contact studs 118 of a switch 120 at the other end 110 of the switch block 106. The switch 120 also comprises a segment 122 arranged to be connected with any one of the studs 118 by a contact member 124 carried by the pivoted member 114 and having parts arranged for engagement respectively with the segment 122 and one of the studs 118.

The inductance of the primary and secondary coils 46 and 50 may be respectively regulated by suitable switches. As shown in Fig. 120 8, the switch for the primary inductance coil 46 comprises a contact post 126 connected with the antenna circuit, and a contact member 128 fulcrumed on the post 126 and movable into engagement with any one of a series 125 of four contact points 130 connected to suitably spaced taps along the coil 46. The switch for controlling the inductance of the secondary coil 50 comprises a post 132 in circuit with the coupling coil 48 and having ful- 130

crummed thereon a contact member 134 movable into engagement with any one of four contact studs 136 electrically connected to the secondary inductance coil at spaced points 5 along the coil. The contact members 128 and 134 extend beyond their fulcrum posts 126 and 132 respectively and are connected to a bar 138, which in turn is operatively connected to a lever 140 fixed to a stud shaft 142 mounted upon and extending through the panel 40 of the cover. The lever 140 is formed with a laterally extending portion 144 pivotally joined to one end of a bar 146, the other end of which is pivotally connected to 15 the member 114 of the switches 104 and 120 so as to operate the switches 104 and 120 simultaneously with the movement of the bar 138 and the consequent operation of the switch members 128 and 134 of the inductance 20 coils. The stud shaft 142 is provided on the side of the panel outside of the chamber 44 of the cover 4 with a knob 148, and arranged for movement with the knob 148 is a pointer 150 co-acting with a segmental scale bar 152 fixed 25 on the exposed side of the panel 40 and preferably graduated to indicate the wave lengths for which the inductances of the coils 46 and 50 are adjusted.

The segment 122 is connected to the grid of 30 vacuum tube 86, the plate circuit of which includes the primary of a step-up transformer 152 supported by a bracket 154 on the inner side of the panel 40. The secondary of the 35 step-up transformer 152 is interposed in the grid circuit of the vacuum tube 88, and the plate circuit of the tube 88 in turn includes the primary of a transformer 156 supported by a bracket 158 mounted on the panel 40 adjacent to the transformer 152. The secondary of the 40 transformer 156 is connected in circuit with the grids of both of the vacuum tubes 90 and 92, and the plate circuit of the tubes 90 and 92 comprises the primary of a transformer 160 supported on the panel 40 by a bracket 45 162. As shown, the brackets 154, 158, and 162 of the transformers 152, 156 and 160 respectively are mounted on the panel 40 adjacent to the edge of the plate 99 which surrounds the opening 94 in which the vacuum 50 tubes are located.

Mounted on the inner surface of the panel 40 between the radio receiving apparatus and the panel is a metal plate 164 which serves as an electrostatic and magnetic shield for the 55 radio receiving apparatus. The metal plate 164 further provides a convenient means for grounding certain of the circuits of the apparatus. The parts of the radio receiving apparatus which are not grounded are insulated from the metal plate 164 and may be supported on posts or legs 165, such as are shown in connection with the primary inductance coil 46. The metal plate 164 is connected to ground by means which will be 60 hereinafter more fully described, and which 65

includes terminal blocks 168 and 170 located respectively on the panel 40 and in the upper part of the main body of the casing of the machine and at the rear of the machine.

As shown most clearly in Figs. 5 and 7, 70 the primary inductance coil 46, coupling coil 48 and primary condenser 52 are housed in a metallic shield 171 shaped to correspond with the inner surfaces of the cover 4. The secondary inductance coil 50 and the secondary 75 condenser 54 are housed in a similar shield (not shown). The shields 171 are mounted on the ground plate 164 in spaced relation to each other and act not only to prevent physical injury to the enclosed parts during the 80 insertion or removal of the panel 40, but also to shield the two circuits from electrostatic and magnetic fields produced by external agencies and to prevent electrostatic or magnetic interaction between the two circuits. 85

The circuit arrangement and manner of operation of the radio receiving apparatus will be best understood by reference to Fig. 9 in which the antenna is designated generally by 172 and is joined to a connecting stud 174 on the terminal block 170 supported on the main body portion 2 of the casing. From the connecting stud 174 the antenna current passes along a flexible lead 176 to a connecting stud 178 on the terminal block 168 located 95 on the panel 40. A wire 180 conducts the current from the stud 178 to the contact post 126 of the switch 128 of the primary inductance coil 46. From the switch 128 the current passes through a smaller or larger portion of the length of the inductance coil 46, according as the switch is arranged to engage the contact point 130 A, 130 B, 130 C or 130 D. As shown, the switch 128 is in contact with the point 130 C, so that a relatively large portion of the inductance of the primary coil 46 is included in the antenna circuit. The antenna circuit is continued through the primary tuning condenser 52 and thence to ground through the metal plate 164. The connections between the metal plate 164 and ground include a wire 181 attached to a connecting stud 182 on the terminal block 168, a flexible lead 184 connecting the stud 182 to a stud 186 on the terminal block 170 and a wire 187 leading from the connecting stud 186 to ground. A second wire 188 connects the stud 186 to the negative side of a battery 166 (Fig. 9).

The coupling coil 48 in the secondary circuit of the radio receiving apparatus is connected at one of its ends to ground by a wire 194 and at its other end to the contact post 132 of the switch 134 of the secondary inductance coil 50. Assuming that the switch 128 of the primary inductance coil 46 is set to contact with the stud 130 C, then by reason of the common operating bar 138 for the switches 128 and 134, the switch 134 of the second inductance coil 50 will be set to contact

with stud 136 C so as to cause the inductance in the secondary tuning circuit of the radio receiving apparatus to correspond with the inductance in the primary or antenna circuit.

5 The end of the inductance coil 50 opposite from its connection with the switch 134 is connected with the grid of the vacuum tube 84, and the secondary tuning condenser 54 is connected in shunt with the coupling coil 48 and inductance coil 50.

10 The vacuum tube 84 acts as a radio frequency amplifier, and its plate circuit is taken from the battery 166 through a wire 196 at a suitable voltage, for example, 110 volts, to 15 a connecting stud 198 on the terminal block 170. The stud 198 is joined by a flexible lead 200 to a connecting stud 202 on the terminal block 168 of the cover 4. A wire 204 connects the stud 202 to a conductor 206 which is in 20 turn connected to the primary coils of the radio frequency transformers 116. As shown, the current passes through the primary coil of the transformer 116 C to the contact stud 110 C of the switch 104. The contact member 25 112 of the switch 104 conducts the current to segment 108 of the switch, and from thence to the plate of the vacuum tube 84. The plate circuit of the tube 84 is completed by connecting the filament of the tube to ground through 30 the metal plate 164.

Each of the secondary coils of the radio frequency transformers 116 is connected at one end to ground through the metal plate 164 and at its other end to one of the contact 35 studs 118 of the switch 120. In the illustrated position of the parts, the current passes from the secondary coil of the transformer 116 C to the stud 118 C, then through the contact member 124 of the switch 120 to the segment 40 122 and from thence to the grid of the vacuum tube 86. The illustrated machine is particularly designed to receive speech, music, etc. sent out from broadcasting stations for the purpose of public information or entertainment. It is customary in broadcasting to impose the speech, music, etc. as audio or tone 45 frequency modulations upon a suitable radio frequency. The vacuum tube 86 serves to detect the audio frequency modulations of the 50 received energy. A condenser 210 and grid leak 212 are preferably interposed in parallel in the grid circuit of the tube 86 between the grid and the segment 122.

As clearly appears from Fig. 3, the radio 55 frequency transformers 116 A, 116 B, 116 C and 116 D progressively increase in size from 116 A to 116 D and have varying constants corresponding respectively to the constants of the primary and secondary tuning circuits when 60 the switches 128 and 134 are in engagement with the contact studs (130, 136) A, B, C and D. It will also be understood that, if the contact members 112 and 124 of the switches 104 and 120 are in contact with the studs 110 A and 118 A, the plate current of the vacuum 65

tube 84 will not pass through the transformer 116 C but will pass through the primary coil of the transformer 116 A, and the grid of the detector tube 86 will be connected to the secondary of the transformer 116 A instead of to 70 the transformer 116 C. Manifestly, if the switches 104 and 120 are set at the contact posts (110, 118) B or D, the radio frequency transformer 116 B or D respectively will be connected in the radio receiving circuit. It 75 will be apparent from the description here- 80 tofore given of the connections between the switches 128, 134, 104 and 120 not only that the constants of the secondary tuning circuit are changed in accordance with changes in the tuning of the primary circuit, but also that the constants of the radio frequency 85 transformer apparatus are correspondingly changed simultaneously with changes in the constants of the tuning circuits.

The plate circuit of the vacuum tube 86 includes the conductor 206 and its connections with the battery 166 and further includes a wire 214 leading from the conductor 206 to one end of the primary coil of the step-up 90 transformer 152. The other end of the primary of the transformer 152 is connected with the plate of the tube 86, and the plate circuit of the tube is completed by grounding the filament of the tube through the metal plate 164. 95 A condenser 216 is provided in the plate circuit of the vacuum tube 86 in shunt with the tube.

The secondary of the transformer 152 is connected at one end with the grid of the vacuum tube 88 which produces the first step of audio frequency amplification and at the other end to a wire 218 and a conductor 220 leading to a connecting stud 222 on the terminal block 168. The connecting stud 222 is in turn joined by a flexible lead 224 with a stud 226 on the terminal block 170, and a wire 228 leads from the stud 226 to the battery 166. As indicated in Fig. 9, the wire 228 is connected to the battery 166 at a point having a potential of -3 volts with respect to the negative end of the filament, inasmuch as excellent results have been obtained in practice from the use of such potential.

The plate circuit of the audio frequency amplification tube 88 includes the primary coil of the transformer 156 and a wire 230 connecting the coil with the conductor 206. The above circuit is completed through the filament to ground at the metal plate 164.

The secondary coil of the transformer 156 is arranged in the grid circuits of both of the vacuum tubes 90 and 92, the arrangement being similar to the so-called "push-pull" circuit, already known in the art. The secondary coil of the transformer 156 is also connected by a wire 232 to the conductor 220 leading to the battery 166 through the wire 228. The plate circuits of the vacuum tubes 90 and 92 include the conductor 206 which is common to

all of the tubes. The connection of the filaments of the tubes 90 and 92 to ground at the metal plate 164 completes their plate circuits. The circuits of the vacuum tubes 90 and 92 afford a second step of audio frequency amplification in addition to the first step produced by the tube 88.

The current for heating the filaments of the vacuum tubes 84—92 is taken from the battery 166 at relatively low potential, such as, for example, +4, 5 volts, and is conducted along a wire 234 to a connecting stud 236 on the terminal block 170 and from thence through a flexible lead 238 to a connecting stud 240 on the terminal block 168. The current then passes to a conductor 242 common to the filaments of all of the vacuum tubes. The heating circuits are completed through the connection of the filaments to the metal plate 164.

The plate circuit of the second audio frequency amplification unit comprising the vacuum tubes 90 and 92 is transmitted by the transformer 160 to a circuit including a wire 244 joined at one end to the ground plate 164 and at its other end to a connecting stud 246 on the terminal block 168. The stud 246 is in turn connected by a flexible lead wire 248 to a stud 250 on the terminal block 170, from which a wire 252 leads to a switch 254. The switch 254 is normally closed so that the current induced in the wire 244 is conducted through a binding post 256 and wire 258 to the telephone 36 mounted on the lateral branch 20 of the horn 12. The return circuit of the telephone is through a wire 260 to the wire 188 and thence to the battery 166 and ground. A condenser 262 is preferably arranged in shunt with the telephone 36 to 40 improve the tone of the speech or music delivered thereby.

In order that external headband or ear telephone receivers may be employed, when desired, to enable reception from distant broadcast stations or to enable one or more persons to receive speech or music from the radio receiving apparatus without emission of sound from the horn 12 of the machine, a metal sleeve 264, Fig. 7, is mounted in the body portion 2 of the casing in electrical connection with the wire 260 between the telephone 36 and the ground wire 188. As shown, the metal sleeve 264 is arranged to receive a plug connected with the headband or ear telephones, and the switch 254 in the circuit of the telephone 36 is arranged in the machine with reference to the sleeve 264, so that the insertion of the plug into the sleeve breaks the circuit of the telephone 36 at the switch 254 and completes a connection from the wire 252 through the headband telephone and the sleeve 264 to the wire 260 and thence to ground.

The radio receiving apparatus of the ma-

chine is thrown into and out of operation by 65 a main switch 266, Fig. 1, mounted on the panel 40 of the cover 4 and connected to any desired part of the circuit arrangement of the apparatus. As shown in Fig. 9, the switch 266 is connected in the circuit 70 234—242, which conducts the heating current to the filaments of the vacuum tubes.

In order to prevent sound communicated to the horn 12 through one of its branches 18 and 20 from entering the other branch and setting up vibrations therein which might interfere with or deleteriously affect the quality of the sound emitted from the horn, the horn is provided with a valve 267, Fig. 6, pivotally mounted at the junction of the branches 18 75 and 20. The valve 267 is arranged to swing between two positions, in one of which, as shown in full lines in Fig. 6, it allows communication between the upright branch 18 and the body of the horn and shuts off communication between the body of the horn and the lateral branch 20, and in the other of which, as shown in broken lines in said figure, it allows communication between the main body of the horn and the lateral branch 20 and 80 shuts off communication between the horn and the upright branch 18. Means is preferably provided for automatically operating the valve 267 so as at all times to allow communication between the main body of the horn 85 and the branch to which sound is being communicated and to shut off communication between the body of the horn and the other branch. As shown, said means comprises an arm 268 fixed to the valve 267 and normally maintained by a spiral spring 270 in the position shown in full lines in Fig. 6, in which the main body of the horn 12 is in communication with the upright branch 18 leading from the phonographic apparatus 90 and is shut off from communication with the lateral branch 20 connected with the telephone 36 of the radio receiving apparatus. In order to cause the valve 267 to be moved from the full line position to the broken line 100 position, as shown in Fig. 6, upon operation of the radio receiving apparatus, an electromagnet 272 of the solenoid type is mounted on the horn adjacent to the arm 268, and the arm 268 is formed with a projection composed 105 of magnetic material and extended within the electromagnet 272. As shown most clearly in Fig. 9, the electromagnet 272 is interposed in the filament heating circuit of the vacuum tubes, so that when the switch 266 is 110 thrown in to initiate the operation of the radio receiving apparatus, the current is caused to flow through the electromagnet. The consequent attraction of the arm 268 by 115 the electromagnet 272 swings the valve 267 from the full line position, shown in Fig. 6, to the broken line position, thereby placing 120 the body of the horn 12 in communication 125

with the branch 20 and shutting off communication between the main body of the horn and the upright branch 18.

As shown in the drawings, the terminal block 168 on the panel 40 of the cover 4 is arranged centrally of the rear end of the panel, and the flexible lead wires 184, 200, 248 etc. are led from the terminal block 168 along the rear inner surface of the cover, where they 5 may be held in place by a suitable cleat 274 to the terminal block 170 which depends from the top plate 22 of the main body portion 2 of the casing. The connecting wires between the terminal block 170 and the battery 166 10 are preferably contained in a single cable 276 extending downwardly to the bottom of the compartment 10 of the casing and leading to contacts 278, Fig. 2, secured to the floor of the compartment 10 and having the wires connected therewith. The radio receiving apparatus is so organized that it requires no external source of power, only replaceable dry batteries being needed for the vacuum tubes, so that the machine may be used irrespective 15 of any external power supply. The batteries may be installed in a single container or box 280, Fig. 4, provided on its bottom with suitable contact plates arranged to engage the contacts 278 when the battery is inserted 20 within the casing. The insertion and removal of the batteries may be further facilitated by the provision of tracks 282 secured to the floor of the compartment 10 and adapted to slidably engage suitably formed parts 25 on the battery box 280. To the end that shocks may be avoided, the closing movement of the cover 4 is controlled by a device 284, Fig. 4, mounted in the compartment 10 of the body portion 2 of the casing and operatively 30 connected with the cover 4 by a link 286, Fig. 2. Further disclosure of the battery 166 and the means for controlling the movement of the cover 4 is believed to be unnecessary, inasmuch as the construction and arrangement 35 of such parts constitute per se no part of the present invention.

Ready and convenient access is permitted to the compartment 10 of the body portion 2 of the casing of the machine by means of a door 286 hinged at 288 at the rear side of the compartment. By reason of the provision of the hinged door 286 the battery box 280 may be easily replaced, and any necessary or desired repairs or adjustments may be readily 50 made to the parts contained in the compartment 10, including the horn 12, the cover controlling means, and the telephone 36.

The amplitude of the speech, or music emitted by the radio receiving apparatus may 55 be increased or decreased by effecting a closer or looser coupling between the coil 48 of the secondary tuning circuit and the primary coil 46 of the antenna circuit. Such an adjustment may be effected by turning the knob 60

290 mounted on the exposed side of the panel 65 40, Fig. 1 and provided with suitable means for indicating the appropriate adjustment for rendering the sounds louder or softer.

From the foregoing, it will be understood that the condensers 52 and 54 in the primary 70 and secondary tuning circuits respectively, of the radio receiving apparatus, the knob 148 for operating the switches 128 and 134 of the inductance coils 46 and 50 and the switches 104 and 120 of the radio frequency 75 transformers 116, the main switch 266, and the knob 290 constitute controlling elements for the radio receiving apparatus and that these elements are extended through the panel 40 of the cover 4 so as to enable them to be 80 operated from the exposed side of the panel. It will also be understood by reference particularly to Fig. 5 that by the provision of the radio receiving apparatus on a movable member, such as the cover 4 of the machine, the 85 controlling elements of the radio receiving apparatus may normally, that is, in the closed position of the cover, or other movable mounting be arranged in close juxtaposition to the controlling elements of the phonographic apparatus so as to conserve space within the 90 machine casing.

For the sake of clearness of illustration, the cover 4, as shown in Fig. 5 of the drawings, is relatively deep, and the controlling 95 elements of the radio receiving apparatus are spaced somewhat further than is necessary from the phonographic apparatus. It will, therefore be seen that the radio receiving apparatus may be installed in a cover of considerably less depth than that shown in Fig. 5 without danger of interference with the sound box 26 or other parts of the phonographic apparatus of the sound reproducing machine. When the cover 4 is in its normal 100 105 or closed position, the controlling elements of the radio receiving apparatus are invisible, so that the sound reproducing machine of the present invention may be caused to present a smooth and unbroken appearance over its 110 115 entire exterior surface. It will be noted, however, that when the cover 4 is opened, the controlling elements of the radio receiving apparatus are moved away from the phonographic apparatus so as to render them not only visible, but also readily accessible to the operator. In fact, when the cover 4 is fully opened, the controlling elements of the radio receiving apparatus are mounted on the front face of the cover, Fig. 1, in an extremely convenient position for actuation by the operator.

Furthermore, the provision of the radio receiving apparatus in the cover of the machine casing enables a sound reproducing machine comprising both phonographic and radio receiving apparatus to be constructed with no greater expense as to the cabinet part 120 125 of the machine than in the case of a phonograph.

graph only, inasmuch as the radio receiving apparatus is mounted in a space, which in a phonograph is totally unused.

The operation of the controlling elements of the radio receiving apparatus is facilitated in the illustrated machine, not only by mounting the radio receiving apparatus on the machine in such a manner as to render its controlling elements extremely convenient for normal operation, but also by the provision of means for indicating the order in which the controls of the radio receiving apparatus should be adjusted. Such indicating means is shown most clearly in Fig. 1 wherein the numerals 1, 2, 3, 4 and 5 are applied respectively to the main switch 266, the wave length controlling means 148, the tuning condenser 54 of the secondary circuit, the condenser 52 of the primary circuit and the knob 290 for regulating the loudness of the sound emitted from the machine. The numbers 1, 2, 3, 4 and 5 indicate to an unskilled operator that in the operation of the radio receiving apparatus the main switch 266 should first be closed, that the knob 148 should then be set in accordance with the wave length of the station which it is desired to receive; that the secondary condenser 54 should next be also adjusted to the desired wave length, and that the condenser 52 which may or may not be graduated should then be turned to the position which affords the best response, the knob 290 being finally set in the proper position depending upon whether it is desired that the speech or music being emitted from the machine be loud or soft. The provision of the above-described means distinct from the controlling elements of the radio receiving apparatus for indicating the order in which the controls should be operated, enables the production for the first time, so far as applicant is aware, of a radio receiving set which can be operated by an unskilled or untrained person with practically as good results as by a skilled operator, and hence constitutes an important practical advance in the development of radio receiving apparatus for purposes of public information and entertainment.

The radio receiving apparatus of this invention may not only be incorporated in new sound reproducing machines comprising radio receiving apparatus and phonographic apparatus, but it may also be applied as a radiola adjunct or receiver to phonographs already constructed and in use. Moreover, by reason of the construction and arrangement of the radio receiving apparatus, it may be applied to existing phonographs having compartments for containing phonographic apparatus and record albums respectively, without increasing the size of the phonograph casing or reducing the available size of any of its compartments, so that the usefulness of the phonograph is in no way affected or its

operation interfered with by the addition of the radio receiver. The radio receiver is also so constructed that it may be applied to any suitable phonograph by a local electrician or carpenter.

Having described my invention, what I claim is:

1. In a sound reproducing machine, a casing comprising a main body portion and a member pivotally mounted on the body portion for movement relatively thereto, phonographic apparatus mounted in the body portion of the casing and radio receiving apparatus mounted on said movable member and comprising controlling elements normally contained within the casing so as to be invisible, said member and said controlling elements being so constructed and arranged as to render the controlling elements visible and readily accessible to the operator solely upon movement of the member relatively to the main body of the casing and a common sound amplifier within the main body portion of the machine which is adapted to be selectively energized by either the phonograph or radio apparatus.

2. In a sound reproducing machine, a casing comprising a plurality of portions pivotally connected together for relative movement, one of said portions constituting a main body portion of the machine, a set of photographic apparatus mounted in one of said portions of the casing, a set of radio receiving apparatus mounted in another of said portions, controlling elements for the phonographic apparatus and for the radio receiving apparatus, said controlling elements being normally contained within the casing so as to be invisible and being located close together so as to conserve space, and said controlling elements and said portions of the casing being so constructed and arranged as to render the controlling elements visible and to separate the controlling elements of one of said sets of apparatus from the controlling elements of the other set of apparatus solely upon relative movement of the portions of the casing, so as to render the controlling elements readily accessible to the operator and a common sound amplifier within the main body portion of the machine which is adapted to be selectively energized by either the phonograph or radio apparatus.

3. In a sound reproducing machine, a casing comprising a main body portion and a cover portion pivotally mounted thereto, phonographic apparatus mounted in the body portion of the casing, radio receiving apparatus mounted on and within said cover portion, and a common sound amplifier within said main body portion adapted to be selectively energized by either the phonographic or radio apparatus.

4. In a sound reproducing machine, a casing, a two-branch horn mounted in the casing,

phonographic apparatus mounted in the casing and connected with one of the branches of the horn, radio receiving apparatus mounted in the casing and connected with the 5 other branch of the horn, a switch for controlling the operation of the radio receiving apparatus and means for automatically shutting off communication between the main body of the horn and said first-mentioned 10 branch upon actuation of the switch to cause communication of sound by the radio receiving apparatus to the other of said branches.

5. In a sound reproducing machine, a casing, a two-branch horn mounted in the casing, 15 a set of phonographic apparatus mounted in the casing and connected with one of the branches of the horn, a set of radio receiving apparatus mounted in the casing and connected with the other branch of the horn, 20 a device for controlling the operation of one of said sets of apparatus, and means for automatically shutting off communication between the main body of the horn and one of said branches upon actuation of the 25 controlling device to cause communication of sound to the other of said branches.

6. In a sound reproducing machine, a casing, a two-branch horn mounted in the casing, two sets of sound reproducing apparatus connected 30 respectively to the two branches of the horn, a device for controlling the operation of one of said sets of apparatus, and means for automatically shutting off communication between the main body of the horn and one of said branches upon actuation of the 35 device to cause communication of sound to the other of said branches.

7. In a sound reproducing machine, a casing, a two-branch horn mounted in the casing, 40 phonographic apparatus mounted in the casing and connected with one of the branches of the horn, radio receiving apparatus mounted in the casing and connected with the other branch of the horn, a switch for controlling 45 the operation of the radio apparatus, common means for automatically controlling communication between the main body of the horn and said branches, said means being normally set to allow communication between 50 the body of the horn and the first-mentioned branch, and connection between said means and said switch for operating said means upon the throwing in of the switch to establish communication between the main body 55 of the horn and the second-mentioned branch and to shut off communication between the main body of the horn and the first-mentioned branch.

8. In a sound reproducing machine, a casing, a two-branch horn mounted in the casing, 60 phonographic apparatus mounted in the casing and connected with one of the branches of the horn, radio receiving apparatus mounted in the casing and connected 65 with the other branch of the horn, a switch

for controlling the operation of the radio receiving apparatus, a valve in the horn mounted for movement between two positions, in one of which it allows communication between the body of the horn and the first- 70 mentioned branch and shuts off communication between the body of the horn and the second-mentioned branch and in the other of which it allows communication between the body of the horn and the second-mentioned 75 branch and shuts off communication between the body of the horn and the first-mentioned branch, a spring for normally maintaining the valve in the first-mentioned position with the body of the horn in communication with 80 the first-mentioned branch and electromagnetic means operable upon the throwing in of the switch to operate the valve so as to establish communication between the body of the horn and the second-mentioned branch 85 and to shut off communication between the body of the horn and the first-mentioned branch.

9. In apparatus of the character described, a branched horn, a telephone connected to 90 one branch of said horn, a phonograph reproducer having communication through a tone arm to another branch of said horn, radio receiving apparatus, means for controlling the energization of said radio receiving apparatus, mechanism for shutting off either of said branches from the main body of said horn, and operating connections between said means and said mechanism for actuating said mechanism upon the energization 95 of said radio receiving apparatus, so that when said radio receiving apparatus is energized, the branch having communication with the phonograph reproducer is shut off from the main body portion of said horn. 100

10. In combination, a branched horn, radio apparatus, phonograph apparatus, a reproducer connected to one branch, a telephone connected to another branch, a valve in said horn for shutting off either of said branches 110 from the main body portion of said horn, and means including a switch for energizing said radio apparatus and simultaneously actuating electro-magnetically said valve so that when said radio apparatus is energized the branch leading to the phonograph reproducer is shut off from the main body portion of said horn and the branch leading to the telephone is placed in communication with the main body portion of the horn. 115

11. In combination, a cabinet, phonographic apparatus mounted in said cabinet, a sound amplifier also mounted in said cabinet, a hollow closure pivotally mounted on said cabinet, and radio receiving apparatus 125 mounted wholly within said closure hollow, said phonographic and radio apparatus being selectively associated with said amplifier for transmission of sound thereto.

ALFRED N. GOLDSMITH.
